UNITED STATES PATENT OFFICE

WILLIAM F. LAUTENSCHLAGER, OF CINCINNATI, OHIO, ASSIGNOR TO THE PEERLESS MACHINERY COMPANY, OF BOSTON, MASSACHUSETTS, A CORPORATION OF MASSACHUSETTS

SAFETY DEVICE FOR PERFORATING MACHINES

Application filed January 17, 1924. Serial No. 686,819.

This invention relates to a safety device for perforating machines of the general type shown in United States Letters Patent, No. 1,434,060, issued to me October 31, 1922.

5 The operation of machines of this character is generally controlled by means of a foot treadle, the depression of which by the foot of the operator is arranged to thrown in a clutch and start the machine which continues 10 in operation so long as the treadle is depressed. A momentary depression of the treadle, however, is sufficient to cause the machine to perform one complete perforating 15 operation and generally these machines are operated in this manner rather than continuously. Whenever, therefore, the foot treadle is moved sufficiently to release the clutch, whether that movement is accidental or intentional, the die-carrying plunger is operated to perforate.

In the ordinary and usual operation of machines of this class there is very little danger of injury if the operator is careful since in presenting the work to the machine 25 she is not, at any time, required to place her hands in jeopardy. The changing of the dies in the machine, however, necessitates the insertion of the hands between the plunger and the work support, and if, while the hands 30 are in this position, the treadle is accidentally moved or depressed sufficiently to release the clutch, the plunger will descend and cut or crush the hands of the operator. It is, therefore, important and desirable to provide 35 means for obviating such accidents because machines of this type are very powerful and rapid in their action, and the results from such accidents are apt to be very serious.

40 The main object of this invention is the provision of simple and efficient means applied to a perforating machine of the character described for preventing the machine from being started in operation while any changes are being made in the dies.

45 A further object of this invention is the provision of such means so constructed that the dies cannot be interfered with or changed except when the machine is in a positive inoperative state in which the depression of the treadle is entirely without effect.

Other objects of the invention will be more specifically set forth and described hereinafter.

55 My invention contemplates the provision in a perforating machine of the character described of means for normally enclosing the die-holding means to prevent access thereto, said means, however, being movable to expose the die-holding means to manipulation in which position the clutch is rendered inoperative so that the machine cannot be started until the enclosing means is returned 60 to normal position.

In the drawings illustrating one form of 65 my invention, Figure 1 is a side elevation of a perforating machine made under the patent hereinbefore referred to and having applied thereto a safety device constructed and designed to operate in accordance with my invention; Fig. 2 is an elevation of the lower 70 portion of the other side of the machine, the safety device being shown in a normal closed position in full lines and in an open position in broken lines; Fig. 3 is a side elevation of 75 the clutch mechanism with treadle operated releasing means as viewed from within the machine; Fig. 4 is a bottom plan view of the clutch on line 4—4 in Figure 1, looking upwardly, the clutch being out; and Fig. 5 is a similar view with the clutch thrown in; and Fig. 6 is a longitudinal sectional view of the 80 dog and pin.

In the drawings illustrating one form of 85 my invention, applied to a perforating machine of the character described in the patent to me hereinbefore referred to, there is shown the frame of that machine and such portions of it as are necessary to properly illustrate the application of this invention. For a more detailed description of the machine, its 90 construction and mode of operation, the said patent may be referred to.

95 Referring to Figure 1, 10 designates the frame of the machine open at the front but otherwise enclosing the operative parts, 12 the die-carrying plunger pivotally mounted on a shaft 14 and 16 indicates the toggle-joints for operating the plunger 12. To the under face of the plunger is secured by end plates 18 and winged nuts 19 the die 20 provid- 100

ed with a multiplicity of perforating tubes 21. A work-support 22, having a plate 23 of soft brass to protect the ends of the tubes 21 in case they pass through a buffer strip 24, holds the work during the perforating operation.

In the drawings the machine is shown as driven by a one-revolution clutch. A belt pulley 25 (shown in broken lines in Fig. 1) is normally loosely mounted upon a hub-block 26 fixed on the end of the main or driving shaft 27; which hub-block carries a clutch-pin 28 adapted to be engaged when in released position by a lug (not shown) on the inner face of the hub of the belt pulley. A spring 29 mounted under compression in a recess 30 in the hub block and bearing at its outer end upon a pin 31 set transversely in the clutch-pin serves to force it outwardly into operative position. Upon the inner end of the clutch-pin 28 is fixed a cam-block 32, its inner end being curved to partially surround and engage the shaft 27 to prevent its turning and its outer end having a bevelled cam surface 33. A locking pin 34 is mounted in bearings 35 and 36 secured to or integral with one side of the frame 10, and when in normal position its upper end is adapted to engage the cam surface 33 and retract the clutch-pin from operative engagement with the belt pulley to permit the latter to run idly. A collar 38 adapted to engage the bearing 35 may be secured to the pin 34 to limit its upward movement and a second collar 39 of larger diameter held in adjusted position by a screw 37 serves as an abutment for depressing the locking pin to release the clutch-pin. For normally holding the locking pin in operative position a helical spring 40 is mounted thereon abutting at one end the bearing 36 and at its other end the collar 39.

Pivots on one end of a shaft 42 projecting from the frame 10 is a lever 44 which is pivotally connected at its upper end by a pin 45 to a strap 46 mounted eccentrically on the hub block 26 and held thereon by the overlapping head of a screw 47 threaded into the inner face of the hub-block. The lever 44 has pivotally mounted on a screw pin 49 on its inner face a dog 50 bored to receive a pin 51 having a shoulder 52 and a reduced portion 53 threaded at its end to receive a nut 54. The bore in the dog 50 in its rear portion is contracted to fit the reduced portion 53 of the pin and a shoulder 55 is therefore formed in the bore which serves as an abutment for a helical spring 56 which is mounted on the pin 51 and abuts at its other end the shoulder 52. The spring being under compression forces the pin outwardly and the limit of this outward movement is regulated by the nut 54 which may be turned on the reduced portion 53 to regulate the projection of the pin from the dog 50. A set nut 58 holds the nut 54 in adjusted position.

The dog 50 is held in a raised position by means of a spring 60 fastened at one end to a screw 61 set in the upper part of the lever 44 and at its other end to a screw 62 set in the dog 50. Two adjustable stops are provided for limiting the movement of the dog up and down, each consisting of a screw 63 threaded through a lug 64 on the lever 44 and held by a set-nut 65. A chain 67 fastened to the dog 50 may be connected to a foot-treadle or other means for starting the machine.

The machine is started whenever the dog through the operation of the foot treadle or other means is depressed sufficiently for the pin 51 by engagement with the collar 39 to pull the locking pin downwardly out of engagement with the cam 33. The spring 29 then forces out the clutch-pin 28 where it is engaged by the lug on the inner face of the belt pulley 25 and the main shaft is rotated. If the treadle is immediately released the locking pin is forced back by the spring 40 into normal position, but if not released, the rotation of the hub-block 26 through the eccentric strap throws the lever 44 outwardly withdrawing the pin from engagement with the collar 39 and the locking pin returns to normal position. In any event the locking pin returns to normal during or at the end of the first half revolution of the hub-block and is in position to engage the cam and disconnect the clutch at the end of one revolution. The release of the treadle after the locking pin has returned to normal permits the dog to return to normal the pin 51 being retracted in the dog against the spring 56 to pass the collar 39 by engagement with it. The stop screw 63 is so adjusted that the dog 50 can not at any time be depressed far enough so that the pin 51 will get under the collar 39 mounted on the locking pin and therefore upon the release of the treadle, the dog will at all times be raised to normal position by the spring 60.

In applying my invention to the machine just described, means are provided for normally preventing access to the die-holding means, said means, however, being movable to expose the die-holding means to manipulation and one form of such means is shown consisting of a frame which encircles and covers the die-holding means, that is, the end-plates 18 and nuts 19. The frame is made up of two arms 70 and 71 connected at their forward ends by a band 72 and is pivotally mounted on a shaft 73 set in the frame 10. In its normal position as shown in Figures 1 and 2, the frame covers the die-holding means and prevents access thereto. In order to expose the die-holding means the frame is pivotally moved into the position shown in broken lines in said figures. For locking the frame in normal position, the arms 71 is provided with a rearward extension 74 near the end of which is pivotally mounted on a screw 75 a locking arm or dog 76 having a

recess 77 near its forward end to receive a pin 78 projecting from the side of the frame 10. A spring 79 secured at one end to a lug 80 formed on the lower side of the dog and at the other end to a screw 81 set in the arm 71 5 holds the dog in locked position. The end of the dog may be curved upwardly to form a finger-piece 82 whereby the operator may pull the dog downwardly to release the frame for forward movement. A hook 83 formed in the end of the extension 74 engages the pin 78 to limit the downward movement of the frame.

In order that the machine may be rendered inoperative whenever the frame is moved away from normal position, any means may be provided for rendering the clutch inoperative and one such means is shown comprising a slide bar 85 adapted to 15 be pushed under the lower end of the locking pin 34 to prevent its withdrawal from the cam-block to release the clutch-pin and start the machine. The slide-bar is pivotally connected by a link 86 to an extension 87 of the arm 70 so that any movement of the frame to expose the die-holding means forces the slide-bar in under the locking-pin. To prevent the machine being started immediately upon the return of the frame to normal position 20 in case the operator's foot happens inadvertently or carelessly to be on the treadle which might result in accident the end of the slide-bar may be provided with a raised portion 90 which will prevent the slide-bar being withdrawn and the frame returned to 25 normal position until the operator takes the foot off the treadle or releases all pressure thereon to permit the spring 40 to force the locking pin into its uppermost position as 30 shown in Fig. 1, which is the only position in which the slide-bar may be withdrawn.

It will be apparent from the foregoing that the operator is absolutely protected from danger when changing the dies and that 35 any carelessness on her part with relation to the foot-treadle cannot start the machine until she has finished her work in relation to the dies and has returned the frame to its normal position.

40 It is to be understood that the form of my invention herein shown and described is merely for purposes of illustration and that the invention may be exemplified by other constructions and may be applied to machines 45 of other forms by changes apparent to one skilled in the art.

What I claim is:

1. A safety device for treadle-operated perforating machines having, in combination, 50 means for normally preventing access to the die-holding means while permitting free handling of the work in the machine, said means being movable to expose said die-holding means to manipulation, and means for rendering the perforating machine inopera-

tive whenever said first-mentioned means is moved out of normal position and until all pressure has been removed from said treadle and said first-mentioned means returned to normal position.

2. A safety device for treadle-operated perforating machine having, in combination, means for normally preventing access to the die-holding means while permitting free handling of the work in the machine, said means being movable to expose said die-holding means to manipulation, means operated by the movement of said preventing means out of normal position for rendering said perforating machine inoperative and means for locking said preventing means against a return to normal position so long as there is any pressure on said treadle.

3. A safety device for treadle-operated perforating machines having, in combination, a guard for normally preventing access to the die-holding means while permitting free handling of the work in the machine, said guard being movable to expose said die-holding means to manipulation, and means operated by said guard whenever moved out of normal position for locking said treadle against movement to start the machine; said means being arranged to lock said guard against a return to normal position so long as the said treadle is subject to any pressure.

4. A safety device for treadle-operated perforating machines having, in combination, a pivotally mounted guard for normally preventing access to the die-holding means while permitting free handling of the work in the machine, said guard being pivotally movable to expose said die-holding means to manipulation, a member connected to said guard and adapted, when said guard is moved out of normal position, to be thrown into a position to lock said treadle against operative movement to start the machine; said member being so constructed that it cannot be retracted from locking position so long as there is any pressure on said treadle.

5. A safety device for perforating machines having, in combination, a guard for normally preventing access to the die-holding means while permitting free handling of the work in the machine and so constructed as to permit the work to be manually positioned for perforating, said guard being movable to expose said die-holding means to manipulation; and means operated by the movement of said guard out of normal position for rendering said perforating machine inoperative so long as said guard remains out of normal position.

6. In a perforating machine, the combination of a reciprocable plunger, a perforating die, means for holding said perforating die upon said plunger, a clutch for connecting the machine to a source of power, a locking pin, a treadle for pulling out said locking pin

to release said clutch to start the machine in operation, a guard normally preventing access to the die holding means while permitting free handling of the work in the machine and a member connected to said guard and adapted to be moved under the end of said locking pin to prevent releasing of the clutch whenever said guard is moved out of normal position to permit access to the die holding means.

7. In a perforating machine, the combination of a reciprocable plunger, a perforating die, means for holding said perforating die upon said plunger, a clutch for connecting the machine to a source of power, a locking pin, a treadle for pulling out said locking pin to release said clutch to start the machine in operation, a guard normally preventing access to the die holding means and a member connected to said guard and adapted to be moved under the end of said locking pin to prevent releasing of the clutch whenever said guard is moved out of normal position to permit access to the die holding means; said member being provided with an abutment on its end to prevent its withdrawal from under the end of said locking pin so long as there is any pressure on said treadle.

8. In a perforating machine, the combination of a reciprocable plunger, a perforating die, means for holding said perforating die upon said plunger, a clutch for connecting the machine to a source of power, a locking pin, a treadle for pulling out said locking pin to release said clutch to start the machine in operation, a guard normally preventing access to the die holding means while permitting free handling of the work in the machine and a slide connected to said guard and adapted to be moved under the end of said locking pin to prevent releasing of the clutch whenever said guard is moved out of normal position to permit access to the die holding means.

9. In a perforating machine, the combination of a reciprocable plunger, a perforating die, means for holding said perforating die upon said plunger, a clutch for connecting the machine to a source of power, a locking pin, a treadle for pulling out said locking pin to release said clutch to start the machine in operation, a guard normally preventing access to the die holding means and a slide connected to said guard and adapted to be moved under the end of said locking pin to prevent releasing of the clutch whenever said guard is moved out of normal position to permit access to the die holding means; said slide being provided with an abutment on its end to prevent its withdrawal from under the end of said locking pin so long as there is any pressure on said treadle.

10. A safety device for perforating machines having, in combination, a guard for normally preventing access to the die hold-

ing means while permitting free handling of the work in the machine, said guard being movable to expose said die-holding means to manipulation, and means whereby the perforating machine is rendered inoperative whenever said guard is in a position exposing said die-holding means.

11. A safety device for perforating machines having, in combination, means for normally preventing access to the die-holding means while permitting free handling of the work in the machine, said means being movable to expose said die-holding means to manipulation and means for rendering the perforating machine inoperative whenever said first mentioned means is moved out of normal position.

12. A safety device for perforating machines having, in combination, a pivotally movable yoke guard for normally preventing access to the die holding means while permitting free handling of the work in the machine, said guard being movable to expose said die holding means to manipulation and a movable slide linked to one end of said guard for rendering the perforating machine inoperative whenever and so long as said guard is out of normal position.

13. In a perforating machine, the combination with a die, die holding means and a treadle operated clutch for connecting said machine with a suitable source of power, of a guard for normally preventing access to said die-holding means while permitting free handling of the work in the machine, said guard being movable to expose said die-holding means to manipulation and a slide member operated by said guard for rendering the clutch inoperative to start the machine whenever said guard is moved out of normal position, said slide member being provided with an abutment to prevent said guard being returned to normal position so long as there is any pressure upon the treadle.

14. The combination with a perforating machine provided with a clutch for connecting said machine to a source of power, a locking pin for normally holding said clutch inoperative and a treadle for withdrawing said locking pin to release said clutch to start the machine, of a safety device comprising a guard for normally preventing access to the die holding means, said guard being movable to expose said die holding means to manipulation, and a member connected to said guard and adapted, when said guard is moved to expose said die holding means, to be thrown transversely across the outer end of said locking pin to prevent said pin being withdrawn to release said clutch.

15. The combination with a perforating machine provided with a clutch for connecting said machine to a source of power, a locking pin for normally holding said clutch inoperative and a treadle for withdrawing said

locking pin to release said clutch to start the machine, of a safety device comprising a guard for normally preventing access to the die holding means, while permitting free handling of the work in the machine, said guard being movable to expose said die holding means to manipulation, and a member connected to said guard and adapted, when said guard is moved to expose said die holding means, to be thrown transversely across the outer end of said locking pin to prevent said pin being withdrawn to release said clutch.

16. The combination with a perforating machine provided with a clutch for connecting said machine to a source of power, a locking pin for normally holding said clutch inoperative and a treadle for withdrawing said locking pin to release said clutch to start the machine, of a safety device comprising a guard for normally preventing access to the die holding means, while permitting free handling of the work in the machine, said guard being movable to expose said die holding means to manipulation, and a member connected to said guard and adapted, when said guard is moved to expose said die holding means, to be thrown transversely across the outer end of said locking pin to prevent said pin being withdrawn to release said clutch; said member being provided with an end abutment to prevent the guard being returned to normal position so long as there is any pressure on the treadle.

25. In witness whereof, I hereunto set my hand this seventh day of January, 1924.

WILLIAM F. LAUTENSCHLAGER.
